(57) **CLAIM**

The ornamental design for a bone cutting rasp as shown and described.

DESCRIPTION

FIG. 1 is a front, top perspective view of a bone cutting rasp showing our new design;

FIG. 2 is a bottom perspective view of the design of FIG. 1; FIG. 3 is a front elevational view of the design of FIG. 1; FIG. 4 is a right elevational view of the design of FIG. 1; FIG. 5 is a left elevational view of the design of FIG. 1; FIG. 6 is a back elevational view of the design of FIG. 1; FIG. 7 is a top view of the design of FIG. 1; and, FIG. 8 is a bottom view of the design of FIG. 1.

The broken lines shown in the drawings illustrate portions of the bone cutting rasp that form no part of the claimed design.

1 Claim, 5 Drawing Sheets
